UNITED STATES PATENT OFFICE

139,003

DESIGN FOR AN ASH RECEIVER

Forrest A. Roberts, Arlington, Va.

Application March 22, 1944, Serial No. 113,009

Term of patent 14 years

(Cl. D85—2)

To all whom it may concern:

Be it known that I, Forrest A. Roberts, a citizen of the United States and a resident of Arlington, in the county of Arlington and State of Virginia, have invented a new, original, and ornamental Design for an Ash Receiver, of which the following is a specification, reference being had to the accompanying drawing, forming a part thereof.

Figure 1 is a perspective view of an ash receiver, showing my new design.

Figure 2 is a sectional view taken along the section line II—II of Figure 1.

Figure 3 is a cross-sectional view taken along the section line III—III of Figure 1.

Figure 4 is a plan view shown in relatively reduced scale.

I claim:

The ornamental design for an ash receiver, as shown.

FORREST A. ROBERTS.
